UNITED STATES PATENT OFFICE.

PAUL F. WILLIAMS, OF CHICAGO, ILLINOIS, ASSIGNOR TO G. & W. ELECTRIC SPECIALTY CO., OF CHICAGO, ILLINOIS, A CORPORATION OF ILLINOIS.

SERIES CUT-OUT.

Application filed May 16, 1925. Serial No. 30,765.

This invention relates to a series cut-out.

One object of the invention is to provide a simple, durable, reliable and efficient series cut-out in which all four cable leads are on 5 one body, whereby the device, complete with all the leads, can be assembled at the factory.

Another object is to provide a series cut-out in which all of the four cable leads are assembled within a single body in a simple 10 and efficient manner to fully protect said leads.

Another object is to provide a series cut-out in which the arrangement of the terminals and contacts is improved, and the means for 15 making and breaking circuits also is improved.

Another object is to provide a series cut-out arrangement which is adapted to meet all of the requirements under service conditions.

20 These and other objects are accomplished by means of the arrangement disclosed on the accompanying sheet of drawings, in which—

Fig. 1 is a vertical sectional view through my improved series cut-out;

25 Fig. 2 is a vertical sectional view through the same cut-out taken in the plane of line 2—2 of Fig. 1;

Fig. 3 is a sectional view similar to that shown in Fig. 1, but showing an insulating 30 handle inserted between the main cable contacts for separating the same and forcing them into engagement with associated lamp cable contacts for completing the lamp circuit, and

35 Fig. 4 is a bottom plan view of my improved series cut-out.

The various novel features of the invention will be apparent from the following description and drawings and will be particularly 40 pointed out in the appended claims.

Referring to the figures of the drawings, it will be noted that my series cut-out includes a single body 10 of insulating material, such as porcelain, having a top wall 11, two side walls 45 12 and two side walls 13, the bottom of the body being left open for the purpose of permitting the four cable leads to be looped up through the open bottom and extended into said body for protecting said cable leads. The 50 two main cable leads are shown at 14, and the two lamp cable leads are shown at 15. Two lamp cable contacts 16 are provided, one being secured to each of the side walls 12 by any suitable means, such as a screw 17, the

head of which may be set in a recess in the 55 wall 12 and covered by an insulating plug 17'. Each of said lamp cable contacts is provided with a laterally extending portion 18, to each of which a lamp cable lug or terminal 19 is secured by any suitable means, such as screws 60 20. The lamp cable leads 15 are secured to the lugs in the usual manner. Two main cable contacts 21, in the form of loops, and two associated auxiliary or arcing contacts 22 are secured to associated metal blocks 23, 65 which metal blocks 23 and contacts 21 and 22 are secured as a unit to the top 11 of the body by suitable fastening means 24, the head of which may be set in a recess in the top 11 and covered by an insulating plug 24'. Each 70 metal block 23 is provided with a laterally-extending portion 25, to which a main terminal lug 26 is secured by screws 27, each main cable lead 14 being secured in the usual manner to the associated cable lug 26. Referring 75 particularly to Fig. 2, it will be noted that the contacts 16, 21 and 22 are centrally arranged within the body 10, and that the main cable lugs 26 are located to one side of the center and the lamp cable lugs 9 are located to the 80 other side of the center, so that the cable leads 14 and 15 pass up into the body on their own respective sides and are separated in a manner to provide proper clearance and avoid confusion.

As shown in Fig. 1 of the drawings, the main cable contacts 21 are in engagement with each other, as also are the auxiliary or arcing contacts 22 for completing a circuit from one main cable lead 14 through said contacts 21 85 and contacts 22 to the other cable lead 14, said circuit being around the lamp circuit, it being noted that the main cable contacts 21 are out of engagement with the lamp cable contacts 16. If it is desired to complete the lamp 90 circuit, such is done by separating the main cable contacts 21 and pressing them into engagement with the associated lamp cable contacts 16, as shown particularly in Fig. 3. In 95 this connection it will be noted that an insulating plug 28, having a handle 29, is used, the plug, when in position, passing upwardly between the main cable contacts 21 and auxiliary contacts 22 for separating said main contacts and auxiliary contacts and pressing 100 said main cable contacts 21 into engagement with the lamp cable contacts 16. The insulating plug 28 passes through an elliptical 105

guide opening 30 formed in the main contacts 21, it being noted that wing portions 31 on the contacts 21 form the actual interengaging portions for completing a circuit through said contacts 21. Likewise the auxiliary contacts 22 are provided with a guide opening 32 for the reception of the plug. Here again wing portions 33 on the auxiliary contacts form the interengaging parts between said contacts.

It will be appreciated that in applying the plug 28 for completing a circuit through a lamp, the plug first enters the opening 30 between the main contacts 21, which opening is smaller than the plug, thereby separating the main contacts 21 and forcing them into engagement with the lamp contacts 16, thereby establishing a circuit through a lamp. Upon continued upward movement of the plug 28, the latter then separates the auxiliary contacts 22, but before said contacts have separated it will be understood that the lamp circuit has been completed and accordingly arcing is prevented. Upon continued upward movement of the plug, its threaded end portion 34 passes into engagement with a threaded socket member 35, which is secured to the top wall of the body 10. By then rotating the plug 28 on its vertical axis it may be positively secured or locked in the position shown in Fig. 3. By thus locking the plug 28 in position, the latter is prevented from accidentally falling from such position, and the circuit connections, as shown in Fig. 3, are maintained. If for any reason it is desired to break the lamp circuit, for example, if trouble has arisen in such circuit, the plug 28 may be loosened from its position shown in Fig. 3 and drawn downwardly, it being noted that the auxiliary or arcing contacts 22 first pass into engagement with each other before the main contacts 21 are permitted to disengage the lamp contacts 16 so that here again, a circuit is established through the contacts 22 before the lamp circuit is broken, arcing in this manner being avoided. Located between the plug 28 and its handle 29 is an enlarged disk or shell portion 36, which protects the operator's hand from passing into engagement with the contacts 21. If, for any reason, the plug 28 becomes lost, any suitable stick may be used for performing the same function. The handle 29 of the plug, however, is provided with an opening 37 for the reception of a chain, by means of which the plug may be secured to a suitable support, such as a telegraph pole, or to the porcelain body 10. The porcelain body is provided with openings 38, through which bolts or attaching means may be passed for securing the porcelain body in its proper position on a pole or other support.

I claim:

1. A series cut-out comprising an integral insulating body forming a housing accessible

only from the bottom, and four cable lugs secured within said body whereby the corresponding cable leads may be looped up through the open bottom and into said body for protecting said cable leads.

2. A series cut-out comprising an integral insulating body forming a housing accessible only from the bottom, two lamp cable contacts secured to said body, two main cable contacts secured to said body, all of said contacts being centrally arranged, and cable lugs electrically connected to said contacts, certain of said cable lugs extending to one side of said contacts and certain others of said cable lugs extending to another side of said contacts to provide clearance for cable leads to be secured to said lugs.

3. A series cut-out comprising an integral insulating body forming a housing accessible only from the bottom, two cable lugs secured to the top of said body and two cable lugs secured to the sides of said body to provide clearance for the free passage of cable leads to be secured to said lugs.

4. A series cut-out comprising a single body, four cable lugs secured to different portions of said body within the latter a pair of said cable lugs being in a different plane than the other pair of said cable lugs to provide clearance for the free passage of cable leads to be connected to said cable lugs.

5. A series cut-out comprising a body having an open bottom, two lamp cable contacts secured to said body, two main cable contacts secured to said body on the opposite side thereof and means tending to be engaged to form a circuit around a lamp circuit, cable leads connected to said contacts entering said body through said open bottom and means for causing separation of said first named means and causing engagement with said means and said associated lamp cable contacts to complete the lamp circuit.

6. A series cut-out comprising a body having an open bottom, two lamp cable contacts secured to said body, two main cable contacts secured to said body on the opposite side thereof and means extending between said contacts and tending to be engaged to form a circuit around a lamp circuit, cable leads connected to said contacts entering said body through said open bottom and means for causing separation of said first named means and causing engagement between said means and said associated lamp cable contacts to complete the lamp circuit.

7. A series cut-out comprising a body having an open bottom, two lamp cable contacts secured to said body, two main cable contacts secured to said body in offset relation to said first named contacts and tending to engage each other to form a circuit around a lamp circuit and extending between said lamp cable contacts, cable leads connected to said contacts entering said body through

said open bottom and means for spreading said main cable contacts and causing their engagement with said associated lamp cable contacts to complete the lamp circuit.

- 5 8. A series cut-out comprising a body having an open bottom, two lamp cable contacts secured to said body, two main cable contacts secured to said body in offset relation to said first named contacts and tending to engage each other to form a circuit around a lamp circuit, auxiliary contacts associated with said main cable contacts, cable leads connected to said contacts entering said body through said open bottom and means for 10 causing separation of said main cable contacts and causing engagement between associated lamp and main cable contacts to complete the lamp circuit before said auxiliary contacts are separated to prevent arcing.
- 15 9. A series cut-out comprising a body, two lamp cable contacts secured to said body, two main cable contacts secured to said body tending to engage each other to form a circuit around a lamp circuit, means for causing separation of said main cable contacts to complete the lamp circuit at said lamp cable contacts, and means for locking in position said last-mentioned means.

- 20 10. A series cut-out comprising a body having an open bottom, two lamp cable contacts secured to said body, two main cable contacts secured to said body in offset relation to said first named contacts and tending to engage each other to form a circuit around a lamp circuit and extending between said lamp cable contacts, cable leads connected to said contacts entering said body through said open bottom and a plug for insertion between said main cable contacts for separating them and pressing them into engagement with the associated lamp cable contacts to complete the lamp circuit.

- 25 11. A series cut-out comprising a body, two lamp cable contacts secured to said body, two main cable contacts secured to said body and tending to engage each other to form a

circuit around a lamp circuit and extending between said lamp cable contacts, a plug for insertion between said main cable contacts for separating them and pressing them into engagement with the associated lamp cable contacts to complete the lamp circuit, and means for locking said plug in operative position.

30 12. In a device of the character described, the combination with a housing open at the base thereof, a plurality of contacts secured therein, pairs of said contacts being secured in offset vertical planes, and means adapted to cause connection between contacts in the 35 different planes.

13. In a device of the character described, the combination with an insulating housing open at the base thereof, a pair of main contacts secured therein, a pair of circuit contacts secured therein, said pairs being secured in different vertical planes, and means connected to said first named contacts and normally causing connection between co-planar contacts and adapted to contact said second 40 named contacts to thereby cause electrical connection between associated contacts in different planes and to thereby disconnect said co-planar contacts.

45 14. In a device of the character described, the combination with an insulating housing open only at the base thereof, a pair of main contacts secured to cables extending therein, a flexible contact means associated with said contacts to normally electrically connect said 50 contacts, a pair of contacts secured to cables disposed on the opposite side of said means, insulating means adapted to operate said first named means to cause electrical connection between pairs of said cables disposed on opposite 55 sides of said first named means and to cause electrical disconnection between said main contacts, and a lock to prevent disengagement of said last named means.

50 Signed at Chicago, Illinois, this 13th day 60 of May, 1925.

PAUL F. WILLIAMS.
